BELT DRESSING MACHINE

Carl J. Hazen, 321 E. Garnet, and Ellis H. Hills, 1955 S. Country Club Drive, both of Mesa, Ariz. 85201
Filed Mar. 8, 1965, Ser. No. 437,924
4 Claims. (Cl. 83—4)

This invention pertains to devices for trimming and sharpening the adjacent corners of the fingers on endless pick-up belts used for picking loose particles of cotton from the ground. The machine on which the belts are used has been patented and is now in use.

It has been found that after use the edges of the transverse slits which pick up the cotton fibers wear and have to be resharpened to keep the adjacent corner edges of the slits sharp and true, and in order to refinish, or sharpen the edges of the belts adjacent the slits we have found that the periphery of the belt may be trued up or shaved so that only fresh live rubber is exposed and that if this is reshaped with the walls of the slits made sharp and true the belt is renewed. The corner edges of these slits may be sharpened by shaving off the worn peripheral parts of the belt. This makes the corners of each finger sharp and true relative to each slit.

One of the objects of the invention is to provide a machine on which the worn belt may be placed and held under tension which has knives for cutting the material of the belts which is usually cured rubber, so that fresh lateral surfaces are exposed, which are at right angles to the transverse slits which pick up the cotton fibers;

Another object includes the provision of a machine which will shave the peripheral surface of a cotton pick-up belt to expose new and fresh rubber adjacent to the new transverse pick-up slits formed in the belt;

Still another object is to provide a means for shaving the peripheral surface and sides of cotton pick-up belts to renew the surface adjacent to the slits so that the edges of the slits, which engage the cotton tufts, are sharp and clean, and will grab the smallest fibers.

Belts here concerned are of the type having a square section.

Other objects will appear hereinafter.

I attain the foregoing objects by means of the devices and machine shown in the accompanying drawings, in which—

FIGURE 1 is a front elevational view of a machine embodying devices constituting my invention;

FIGURE 2 is a rear elevational view thereof;

FIGURE 3 is a plan view showing the details of the operation of the cutting head on the belt being trimmed and rejuvenated;

FIGURE 4 is an enlarged perspective view of the belt cutter;

FIGURE 5 is an enlarged sectional view of the belt cutter;

FIGURE 6 is a section showing the trimming knife in operation;

FIGURE 7 is a plan view showing the trimming knife housing;

FIGURE 8 is a section showing particularly means for lubricating and cooling the trimming knife.

The machine is supported on a rectangular frame 2, having vertical legs 3, at each of its corners. Transverse shafts 5 and 6 are operated on bearings 7 held within the frame, in bearing guides 7a (see FIG. 2).

On the near ends of the shafts, as viewed in FIGURE 2, there are pulleys 5a and 6a having peripheral grooves to receive and hold a belt to be treated. Shaft 5 is driven by a motor 8 so that the belt is driven over both pulleys at a predetermined regulated speed. Midway of the top lay 10 of the belt there is a guide channel which forms a base against which the pressure of the grooving knives

2

may work. At the left end of the belt, and above and extending in a radial direction out from pulley 5a, there is a circular cutting or trimming knife 12 operated by motor 14, which has a vertically positioned shaft 11, and may be vertically adjusted by screw 16. This trimming knife 12 is of the rotary type and has a sharpened periphery which contacts the belt at a tangent to its periphery to shave off the outer surface and remove the worn and jagged edges of the transverse pick-up slots 4a on the belt's outer face. This knife is cooled and lubricated by fluid introduced by pipes 17a and 17b. Excess fluid drops into sump and storage tank 24, as at 31, from which it is circulated by pump 19a. At the outer end of pipe 17, the flow is divided into pipes 17a and 17b which terminate in spray nozzles directed to the upper and lower faces of the knife 12, respectively. The lubricant is soapy water or its equivalent. The direction of circulation is shown by arrows 20, FIGURE 2.

The belt to be trimmed is first placed over the pulleys 5a and 6a and then tightened to proper tension by a hydraulic piston 22 operating in hydraulic cylinder 23 controlled by valve 30. Due to the fact that considerable tension stress is required, the hydraulic means are used in preference to screw means.

The grooving knives 15 are shaped to cut semi-circular grooves 35 on the peripheral face of the belt. Since they have no lateral cutting movement they are heated sufficiently to soften the rubber. This is done electrically, in a manner similar to an electric soldering iron. Electrical connections are made through cord 37. In this way the newly cut and shaved outer surface of the belt is provided with new deeper cut grooves.

When worn belt 10 is placed over pulleys 5 and 6, it is tightened by the hydraulic piston 22 operating in cylinder 23 until the two lays (upper and lower) are straight. The drive pulley 5 is then rotatively operated by motor 8 so that the belt travels in a counter-clockwise direction (FIG. 1). At the same time, knife 12 is operated to remove desired peripheral portion of the belt material and provide a new outer peripheral portion which will intersect the edges of all transverse slots at right angles. This operation rejuvenates the belt and makes it somewhat smaller on the outside. However, in practice, we have found that belts are usually made with an excess thickness and the removal of this outer layer does no harm to their salvaging operation.

We claim:

1. A pick-up belt dresser comprising a rectangular frame, a pair of shafts extending transversely through said frame, grooved pulley wheels on the ends of said shafts, bearings in said frame journaling said shafts, the bearings on one shaft being slidably adjustable toward and from the bearings of the other shaft so that said pulleys may be moved to tighten or loosen a belt placed over said pulleys by hydraulic means for moving said bearings; power means for rotating at least one of said pulleys to move a belt to be dressed placed over said pulleys and supported thereon; a rotary dressing knife having a peripheral cutting edge, disposed on said frame with its cutting edge tangentially engaging the outer surface of said belt; means for adjustably moving the cutting edge of said rotary knife toward or from the outer surface of said belt on said pulleys; and power means for rotating said rotary knife.

2. A pick-up belt dresser comprising a rectangular frame, a pair of shafts extending transversely through said frame, grooved pulley wheels on the ends of said shafts, bearings in said frame journaling said shafts, the bearings on one shaft being slidably adjustable toward and from the bearings of the other shaft so that said pulleys may be moved to tighten or loosen a belt placed over said pulleys by hydraulic means for moving said

bearings; power means for rotating at least one of said pulleys to move a belt to be dressed placed over said pulleys and supported thereon; a rotary dressing knife having a peripheral cutting edge, disposed on said frame with its cutting edge tangentially engaging the outer surface of said belt; means for adjustably moving the cutting edge of said rotary knife toward or from the outer surface of said belt on said pulleys; and power means for rotating said rotary knife; a groove cutting knife having a pivotally supported supporting frame to move said knives to and from the surface of a belt supported on said pulleys, and means for heating the groove cutting knives while cutting said grooves.

3. A pick-up belt dresser comprising a rectangular frame, a pair of shafts extending transversely through said frame, grooved pulley wheels on the ends of said shafts, bearings in said frame journaling said shafts, the bearings on one shaft being slidably adjustable toward and from the bearings of the other shaft so that said pulleys may be moved to tighten or loosen a belt placed over said pulleys by hydraulic means for moving said bearings; power means for rotating at least one of said pulleys to move a belt to be dressed placed over said pulleys and supported thereon; a rotary dressing knife having a peripheral cutting edge, disposed on said frame with its cutting edge tangentially engaging the outer surface of said belt, means for adjustably moving the cutting edge of said rotary knife toward or from the outer surface of said belt on said pulleys; and power means for rotating said rotary knife; a groove cutting knife having a pivotally supported supporting frame to move said knives to and from the surface of a belt supported on said pulleys, and means for heating the groove cutting knives while cutting said grooves; means for lubricating said rotary knife including a spray of water soluble lubricant directed on the cutting edge of said knife during the cutting operation.

4. A pick-up belt dresser comprising a rectangular frame, a pair of shafts extending transversely through said frame, grooved pulley wheels on the ends of said shafts, bearings in said frame journaling said shafts, the bearings on one shaft being slidably adjustable toward and from the bearings of the other shaft so that said pulleys may be moved to tighten or loosen a belt placed over said pulleys by hydraulic means for moving said bearings; power means for rotating at least one of said pulleys to move a belt to be dressed placed over said pulleys and supported thereon; a rotary dressing knife having a peripheral cutting edge, disposed on said frame with its cutting edge tangentially engaging the outer surface of said belt; means for adjustably moving the cutting edge of said rotary knife toward or from the outer surface of said belt on said pulleys; and power means for rotating said rotary knife; a groove cutting knife having a pivotally supported supporting frame to move said knives to and from the surface of a belt supported on said pulleys, and means for heating the groove cutting knives while cutting said grooves; means for lubricating said rotary knife, comprising a case enclosing the cutting area of said knife having an upper side and a lower side; a spray nozzle directing a spray of water soluble liquid lubricant on the knife edge while cutting, an outlet catching excess liquid, a sump below said outlet, a power driven circulating pump in said sump forcing said liquid from said sump to said spray nozzle.
